UNITED STATES PATENT OFFICE.

CARL I. HAHN, OF PHILADELPHIA, PENNSYLVANIA.

ARTIFICIAL LEAF AND PLANT.

SPECIFICATION forming part of Letters Patent No. 252,762, dated January 24, 1882.

Application filed June 1, 1881. (No model.)

To all whom it may concern:

Be it known that I, CARL I. HAHN, a subject of Germany, residing in the city and county of Philadelphia, and State of Pennsylvania, have invented a new and useful Improvement 5 in Artificial Leaves and Plants, which improvement is fully set forth in the following specification and accompanying drawings, in which—

Figure 1 is a perspective view, partly sectional, of a plant embodying my invention. Fig. 2 is a view of the under side of a leaf.

Similar letters of reference indicate corresponding portions in the two figures.

My invention consists in forming artificial leaves, substantially in a manner hereinafter fully set forth, whereby they closely resemble nature, may be quickly and inexpensively produced, and are strong and durable.

It also consists of a novel mode of forming 20 the stems, whereby they are firm and durable, and may be quickly and inexpensively produced.

Referring to the drawings, A represents leaves, which are formed as follows: I take 25 manila or other suitable paper and stamp or press and cut the same into the shape of leaves, which are dipped into colored beeswax, or other suitable wax or material, in a hot state, so as to stiffen the paper and impart to it a glossy 30 appearance and water-proof nature and finish the back of the leaves. The faces of the leaves are then painted or printed with oil colors, so as to produce the various tints and shading.

It will be seen that the leaves present a 35 natural appearance both in shape, veins, ribs, color, &c., and are light, inexpensive, and quickly produced, and, furthermore, may be washed without injury and kept clean and fresh.

The stems B are formed of knitted or braided 40 fibrous material, the connecting end of each of which is spread out or flaring by separating the fibers or threads, forming a broad bed, a, preferably somewhat of the form of a socket or cup, which bed is dipped into glue or other 45 adhesive material, and applied to the back of the leaf prior to dipping the latter in wax, an inwardly-projecting portion of the leaf entering said bed, as in Fig. 1; or the fiber is glued 50 along its length to the back of the leaf, as in Fig. 2, the leaf and stem being firmly pressed together, so that they adhere and are securely connected. A piece or core of wire, b, is then passed through the center of the fibrous stem,

thus stiffening the stem, and the latter is 55 dipped into hot wax or other suitable material, beeswax being preferred, the effect whereof is to coat or saturate the fiber, fill the spaces between the wire and fiber and the braiding, and impart a proper body to the stem. 60

The coloring of the stem is accomplished by the employment of colored wax or by dyeing the braided or knitted fabric.

By means of a proper tool the surface of the stem is rubbed or "teased," while the wax is 65 still hot, the effect of which is to impart to the stem an appearance of fuzz.

If desired, the paper leaves and material of the stem may be colored or printed prior to the application of the wax. 70

Leaves made according to my method have all the appearance of those made of solid wax, but are cheaper and more durable, as I save wax and the paper is stiff without being brittle.

I am aware that it is not broadly new to 75 make artificial leaves of paper covered with wax; also, that it is not new to color wax with artists' colors.

Having thus described my invention, what I claim as new, and desire to secure by Letters 80 Patent, is—

1. As a new article of manufacture, a leaf formed of paper, shaped and cut, coated with wax, and painted or printed with oil color, the latter being on the surface of the wax coating, substantially as and for the purpose set forth. 85

2. In artificial leaves and flowers, stems formed of fibrous material having the ends of the threads thereof spread out, making sockets, flaring beds, or places of attachment, as at a, substantially as and for the purpose set forth. 90

3. Stems formed of fibrous material with a core of wire and saturated or coated with wax, substantially as and for the purpose set forth. 95

4. Stems formed of fibrous material saturated or coated with wax, rubbed or teased, substantially as and for the purpose set forth. 100

5. Paper leaves coated with wax and colored in oil, in combination with stems of fibrous material having stiffening-cores and wax coatings, substantially as and for the purpose set forth.

C. I. HAHN.
